CLAIM

The ornamental design for a blank for packaging container, as shown and described.

DESCRIPTION

The sole FIGURE is a top plan view of an unfolded blank for packaging container.

The dash-dot broken lines shown are included for the purpose of illustrating boundaries of the blank for packaging container that form no part of the claimed design.

The dash-dot broken lines shown are included for the purpose of illustrating fold lines of the blank for packaging container that form no part of the claimed design.

The solid lines inside the boundaries of the claimed design show surface ornamentation.
